United States Patent Office

Des. 186,559
Patented Nov. 3, 1959

186,559

CHECK FILE GUIDE OR THE LIKE

John L. Talley, Cedar Rapids, Iowa, assignor to Le Febure Corporation, Cedar Rapids, Iowa, a corporation of Delaware

Application April 6, 1959, Serial No. 55,344

Term of patent 14 years

(Cl. D74—2)

I claim:

The ornamental design for a check file guide or the like, as shown.
